DUPLICATING MACHINE

Ludwig W. Wagner, San Antonio, Tex., assignor
to Ditto Incorporated, a corporation of West
Virginia

Application October 25, 1929, Serial No. 402,475

37 Claims. (Cl. 101—132)

My invention relates to apparatus for making a considerable number of copies of a written, typewritten or otherwise produced master sheet or the like, by the use of a gelatinous impression 5 pad, sheet or band in machines of the character stated. The master sheet is spread face down on the gelatinous impression sheet, whereby the matter to be copied is taken on by the gelatinous surface, after which the master sheet 10 is removed. Blank sheets are then placed over the impression sheet and brought into intimate contact therewith by suitable means such as a platen roller.

Apparatus of the character stated as heretofore provided may be roughly divided into two broad classes; in the first class the bed is flat and the cooperating movable element or platen roller rolls over the bed rectilinearly; the other class 15 is one in which the bed is of cylindrical form.

My invention in its complete aspect has to do 20 principally with the cylindrical bed type of apparatus, though it may also be adapted to the flat bed type of apparatus. Since the preferred embodiments of my invention relate, however, to 25 the cylindrical type I shall confine my illustration and description to two embodiments of the invention in the cylindrical type of machines.

In the cylindrical type of machines the printing band which receives the impression from the master sheet and later transfers it to the copy sheets, 30 is stretched over the surface of a drum or cylinder, the idle portions of the printing band being wound on spools carried by the cylinder; a fresh surface being obtained as often as required by winding 35 up the used surface on one spool and simultaneously drawing onto the surface of the cylinder a fresh section from the other spool.

Considerable difficulty has been experienced in 40 the practical use of such machines arising out of the excessive friction of the printing band on the surface of the cylinder, which latter usually has a surface covering of canvas, felt or like material to afford a suitable backing for the printing band, the curved form of the bed making the operation 45 of drawing on a fresh surface difficult and likely to be attended by injury to the band itself or to the winding and unwinding mechanism. While attempts have heretofore been made to avoid this 50 difficulty they have not, in my opinion, proven all that is desired; it is therefore one of the objects of my invention satisfactorily to overcome such difficulty and render the band shifting operation easy, safe and fully effective in reducing the danger of injury to the gelatinous band.

Again, in the machines of the kind to which

my invention relates, the copy sheet is fed to the gelatinous impression or placed down in such manner as to afford a considerable surface contact between the sheet and the impression surface. Since the adhesion between the copy sheet and 60 the impression surface is considerable, the gelatinous impression surface is frequently damaged in removing the copy sheet therefrom. Another object of my invention, therefore, is to overcome this objectionable feature and so to apply the 65 copy sheet to the impression surface as to reduce the area of contact at any one time to the smallest possible degree.

Further, the invention has for an object to provide means whereby, in making the copy, the 70 copy sheet will have substantially not more than a line of contact with the gelatinous surface, wherefore I provide means to peel the copy sheet from the gelatinous surface practically as fast as it is brought into contact therewith. 75

Further, it is an object to provide means to apply and remove the copy sheet to and from the impression surface by a rolling action in one direction and one movement only.

Further, it is an object to provide a platen 80 roller in association with a plurality of paper gripping rollers so cooperatively disposed with each other that the gripping rollers will be held in yielding pressure contact with the platen roller only while the copy sheet is in place and is 85 being held by the rollers and applied to the impression sheet.

Further, it is an object of the invention to provide a machine in which the platen roller is automatically separated from the cylinder or 90 bed and from the gripping rollers by the time a new copy sheet is to be fed into place.

Further, it is an object to provide the machine with a paper stop cooperatively associated with the platen in such manner as to perform 95 a dual function, namely the function of a front edge stop for the paper to position it properly there, and second to function as a deflector to cause the paper to pass from the platen outfeed gripping rollers in a proper direction and 100 manner to be clearly discharged from the machine or onto a copy-sheet receiver.

Further, it is an object to provide means to apply the sheets to the impression surface in such manner as to avoid wrinkles. Heretofore, 105 in machines of the general kind to which the invention relates, the paper to be printed very frequently wrinkles and for that reason uneven copies are obtained. This fact is also the cause of the well-known trouble of the blank sheet slip- 110

ping between the platen and the single gripping roller heretofore used.

Another object is to provide a machine in which the cylinder may be continuously rotated in the same direction thereby causing the copy sheet to contact the impression sheet but once in its movement and enabling copy sheets to be fed into the machine in rapid succession which is bound to make for clear, sharp-cut copies. This improvement over existing machines enables the passing of the blank after feeding into engagement with the impression band, printing the sheet and depositing the printed copy automatically on the receiving tray or apron without having to touch the paper and with one forward movement. Existing machines with which I am familiar require a forward stroke to pass the blank paper and this forward stroke must be stopped in time so that the rear edge of said blank paper will not pass through the rollers, as a certain margin is required to effect the return movement for the purpose of withdrawing the printed copy; therefore two movements are required in the machines of the prior art.

Further, it is an object to provide a machine in which provision is made for the perfect registration of the copy sheets with the impressions made by the master sheet.

Other objects will in part be obvious and in part be pointed out hereinafter.

To the attainment of the aforesaid objects and ends, my invention consists in the novel features of construction and in the combination, connection and arrangement of parts, hereinafter more fully described, and then pointed out in the appended claims.

In the drawings:

Figure 1 is a side elevation of the preferred embodiment of my invention.

Figure 2 is a plan thereof, the table plates and receiver being removed.

Figure 3 is a vertical section on the line 3—3 of Figure 2 showing the position of the parts when the platen roller has been raised and a blank copy sheet has been put into place.

Figure 4 is a view similar to Figure 3 showing the position of the parts during the making of copy.

Figure 5 is a vertical cross section on the line 5—5 of Figure 4.

Figure 6 is a detail perspective view of one of the spool holding ratchets and its associated spring clip.

Figure 7 is an enlarged detail section of the ratchet mounting.

Figure 8 is an enlarged detail section illustrating the securing means of the adjustable cam track.

Figure 9 is a vertical cross section on the line 9—9 of Figure 1.

Figure 10 is an enlarged detail part section and part elevation of the ratchet controlling means.

Figure 11 is an enlarged detail perspective view of one of the stop bearing elements used for the reception of one end of the spools.

Figure 12 is an enlarged detail face view and part section illustrating the slide support.

Figure 13 is an enlarged detail section of the paper deflector.

Figure 14 is a side elevation of a modified form of my invention.

Figure 15 is a detail sectional view of the platen roller operating means shown in Figure 14.

Figure 16 is a face view and part section of the

parts shown in Figure 15 with the platen roller in the raised position.

Figure 17 is an enlarged detail section showing the spring releasing means in operation.

In the drawings, in which like numerals and letters of reference indicate like parts in all of the figures, 1 represents the side frame members which are provided (preferably) with sound deadening suction-gripping feet 2 of rubber, or other suitable material. A central cross member 3 is provided and has bearing apertures for the journals 45 of the drum shaft 44. Above the cross member 3 are cross bearing supports 4 for the feed roller unit.

Upper horizontal bars 5 of the side frame members are provided with grooves for the reception of the extensible table plates 7 and 8 onto which the copy sheets are initially laid.

Suitably disposed tie rods and spacers 6 connect the side frame members 1 together in spaced relation and thereby cooperate with the same to provide a rigid frame or support for the bed and platen units.

Projecting upwardly from the horizontal bars 5 over the table plates are uprights 9 for supporting a guide rod 10 on which is slidably, laterally of the table, suitable side alignment guides 11 for the paper, the sleeves 12 of which guides have bearing on the rod 10 and are held in their respective positions by set screws 13 or any other suitable devices.

Mounted rigidly on the cross bars 4 and secured to the horizontal bars 5 in any suitable manner are vertical slide supports 14 having slideways 15 for the reception of the slides 19, the latter being held in the slideways by means of removable slide retaining plates 16. The plates 16 are provided with vertical slots 17 and 18 which properly align with one another and the purpose of which will later appear.

The slides 19 are provided with bearings 20 for the bearing ends 29 of the shafts 27 of the platen roller 28. The slides are also provided with studs 21 carrying anti-friction rollers 22 by means of which the slides are raised as will presently be clear.

The slides 19 are continuously pulled downwardly by slide roller springs 23, the latter being provided with tensioning bolts 24 that pass through the cross bars 4 and tension adjusting nuts 25 as best indicated in Figures 1 and 5 of the drawings. The slides have connecting hooks 26 to which the springs are attached.

At the upper extremities of the supports 14 are bosses 30 which carry studs 31 on which the paper gripping roll carrying arms 32 and 33 are pivotally mounted. There is a pair of arms 32 and 33 at each side of the machine and the arms of a pair are pressed together by an arm closing spring 34 as indicated. 36 and 38 designate the paper gripping rollers, the shaft ends 35 and 37 thereof being rotatably mounted in the free ends of the arms 32 and 33 respectively.

Associated in a cooperative manner with the platen roller 28 and located above the paper gripping roller 38 is a combined paper stop and deflector member 39. This member, as will be clear, from the drawings, when in one position rests against a back stop 43 and has its vertical surface 41 arranged to function as a front-edge paper stop. The member 39 is pivoted at 40 and has a weighted end so designed that it may be swung from its vertical position against the back stop 43 to an approximately horizontal position by gravity. The curved surface 42 of the combined

paper stop and deflector member, at the outer end thereof, rests against the platen roller so that when the platen roller is moved upwardly to raise it above the gripping rollers to a position whereby a fresh copy sheet may be inserted, it will also move the member 39 upwardly to its vertical position, and conversely as the platen roller is lowered again gravity will cause the member 39 to follow the platen roller and assume an approximately horizontal position.

When in the horizontal position the paper being fed upwardly between the platen roller 28 and the out-feed one 38 of the paper gripping rollers will engage the then under-surfaced 42-41 of the member 39 and be deflected outwardly in a substantially horizontal direction so that it may fall downwardly onto the receiving apron or tray 76 to be later more clearly explained.

The drum shaft 44 is the main operating shaft of the machine and has the reduced bearing ends 45 heretofore referred to which are journalled in the bearings provided in the member 3 of the end frames 1. The drum is composed 25 of end disks 46 which are provided with openings 47 for the purpose of reducing weight and also to enable access to be had to the interior of the drum.

48 designates a pair of ratchets, one for each 30 spool that carries the impression or printing band 67. The drum also includes a periphery or cylindrical surface 65 that is provided with an opening through which the printing band 67 may pass into the drum for winding and unwinding 35 on the respective spools.

The ratchets 48 have shafts 49 which are rotatably mounted in suitable bearings 50 in the end disks 46 of the drum. These stub shafts 49 of the ratchets 48 have squared ends 49x for the 40 reception of keys or gears by which the ratchets may be turned for winding purposes.

51 designates retainers for holding the ratchets 48 in their bearings, it being understood that the ratchets need not be removed in order to remove and replace the spools. The shafts 49 of the ratchets 48 have slotted squared bearing sockets 52 for the reception of the squared ends of the shafts of the printing spools 57 and 58, there being friction-spring retainer clips 53 on 50 the shafts 49 which may be turned around to close the sides of the slots 52 and retain the shaft ends of the printing band spools therein.

Directly opposite the ratchets 48 on the other end disk of the drum there is mounted stop bearing elements 54 which are also provided with receiving slots 55 for the reception of the adjacent shaft ends of the spools 57 and 58 and these stop bearing elements 54 are also provided with friction-spring retaining clips 56 similar 60 in construction and function to the clips 53.

The ratchets 48 are engaged by double-acting pawls 59 that are pivoted at 60 to the ends 46 and are shifted by means of bell crank shifting levers 62 fulcrumed at 63 and having spring-pressed fingers 64 to engage in recesses 61 in the double-acting pawls.

The drum is provided on its periphery with a suitable backing pad 66 of rubber, felt, or other suitable material.

70 In order to reduce the area of contact between the gelatinous band 67 and the surface of the backing pad over the periphery of the drum I provide a pair of arms 69 which are pivotally mounted within the drum in such manner that they may lie wholly within the circumference

of the drum if desired. These arms 69 carry printing band spreader rollers 68 over which the gelatinous band is passed; the band also passing over idler rollers 82, the purpose of which will soon appear.

The pivoted arms 69 are provided with spring elements 70 that continuously tend to move the arms outwardly on their pivots and carry the spreader rollers 68 from a position within the circumference of the drum to a position outside of the same, thereby taking the gelatinous band and lifting it out of contact with the drum throughout a large portion of the length of the periphery of the drum. The amount of band left in contact with the drum when the arms 69 are swung out will, of course, depend in a measure on the length of those arms. In practice the arms will be made of such length as to lift the band from the drum throughout more than three-quarters the circumferential length of the drum's periphery.

In order automatically to throw out the arms 69 when the tension on the band is slackened I may provide springs 70 which tend continuously to move the arms to their outward positions.

In the preferred embodiment of the invention it will be observed that the springs 23 continuously tend to keep the platen roller in contact with the drum. As the platen roller must, however, be raised for the insertion of the copy sheets, I prefer to accomplish that movement automatically by providing the drum with adjustable platen roller raising and holding-up cam plates 71, 72, 73 mounted on the outside of the drum heads or end disks 46 by means of suitable set screws 74 and retainer guides 75. The cam plates 72 and 73 may be adjusted angularly around the axis of the drum so as to reduce or increase the effective operative areas of the printing surface. When the cam plates 71, 72, 73 are extended to their maximum degree the printing act occurs through only a short arc of the drum, whereas when these cams are contracted to their maximum degree the printing arc is correspondingly increased to its full capacity.

76 designates the work receiving apron or tray which is provided with a lower stop 77 and at the upper end carries a sheet directing baffle 78 having an inwardly bent end 79 to form a shoulder with the apron 76. The apron is supported on certain of the rods 6 by means of slotted ears 80.

An operating handle 81 is attached to an end of the main shaft by means of which this shaft may be turned to impart rotation to the drum, it being understood that the drum heads 46 are non-rotatably mounted on the shaft 44.

It should be understood that in applying the master sheet to the impression surface, after the master sheet has had its front edge located by movement of the combined stop and deflector element and the platen has been lowered to place the master sheet into contact with the impression surface, the stop and deflector element and the out-feed paper gripping roller are raised (by hand or any other suitable mechanism) and the advance end of the master sheet is permitted to drop down onto the impression band. After this the platen roller is rolled by means of rotating drum to lay the master sheet. Thus, the master sheet is laid in full surface contact with the impression sheet or band where it is permitted to remain for such length of time as necessary to enable the impression sheet to take on the impression of the required density. The master sheet is then removed by hand.

So far as described the manner in which the

140

145

150

preferred embodiment of the invention operates is as follows: Assume that the master sheet has been laid over the gelatinous surface so that the gelatinous surface may take its impression therefrom and the master sheet has then been removed. Assume the parts are now in the position illustrated in Figure 3. At this time the platen roller will have been raised by the cams 71, 72, 73 to lie above the rollers 36, 38, which rollers, of course, are held toward one another by the spring 34, suitable stops 122 being provided if desired to prevent the rollers 36 and 37 from coming entirely into contact with each other when the platen roller is in its uppermost position.

15 A paper sheet is now fed along the table until its front edge rests against the stop surface 41 of the member 49. The handle 81 is then turned in a clockwise direction to cause the drum to turn in the direction of the arrow in Figure 3 which 20 brings the cams 71, 72, 73 from under the pins 22 and permits the springs 23 to lower the platen roller. The lowering of the platen roller presses the paper sheet downwardly between the rollers 36 and 38, which rollers hold the sheet along the 25 platen roller in such manner that the sheet contacts the gelatinous surface in a line contact only and permits the combined stop and guide unit to fall so as to deflect the paper toward the tray 76. As the paper leaves the platen unit, after impression, it falls upon the receiver and is held for removal therefrom manually.

It will be noted that by reason of the adjustable side guides for the paper and the front stop, complete or exact registration of the copy sheet 35 with the master sheet's impression on the gelatinous surface is obtained.

The second embodiment of my invention is illustrated in Figure 14 to Figure 17 inclusive, by reference to which it will be seen the bed unit 40 is the stationary one and the platen unit is the movable one.

The bed unit comprises a base which consists of end frames 83 between which is a cylindrical segment plate 84, cross braces 85 being provided 45 to connect the parts 83 and 84 rigidly together as one.

The construction of the spools, their bearings, ratchet and pawl mechanism, etc., etc., may be the same as in the first embodiment of my invention as may also be the impression band spreader, etc. Therefore, such parts of the bed unit used in the second embodiment of my invention as are or may be of the same construction as those in the first embodiment, bear the same reference 55 numbers in the figures illustrating the second embodiment and a description thereof need not be here repeated.

The platen unit, however, differs somewhat from that of the first embodiment of my invention and will now be described.

50 Upright bars 86 are pivoted to the side plates 83 of the frame as at 87 and have their upper ends bent toward each other at right angles as at 88 to carry posts 89 on which are springs 103. 65 Connecting or tie bars 91 or 102 are also mounted on the posts 89 as shown.

The posts 89 are provided with threaded nuts 90 constituting stops which may be, for ornamental purposes, of spherical form if desired.

70 The upright bars 86 are provided with removable plates 92 which cover slideways 93 in those bars, in which slides 93 are held to operate.

75 On the plates 92 are mounted spring latches 94 secured at 95 and having releasing fingers 96, these latches being adapted to have their

latching fingers 120 engaged with apertures 121 in the slides 98 at times.

The end frames 83 also carry latch releasing elements 97 which are adjustably mounted so that their positions may be changed at will and which, when the fingers 96 are brought into engagement with the same will serve to release the latch fingers 120 from the apertures 121 so as to permit the springs 103 to function to elevate the slides 98 and consequently the platen roller 100 which has its shaft ends journaled in bearings 99 in the slides 98. The slides have angled ends 101 apertured to fit on the posts 89, the springs 103 being located between those ends and the cross bar 102.

90 Paper gripping roller carrying arms 104 and 105 are pivoted at 108 to adjustable plates 109 which are adjustably mounted on the upright bars 86. The arms 104 and 105 carry paper gripping rollers 106 and 107 and are link-connected at 110 with the axle 112 of the platen roller 100, the links being pivoted to the axle and also pivoted at 111 to the arms 104, 105.

95 A combined paper stop and deflector element 113 is pivotally mounted on the arms 105 and 100 a back stop 114 on those arms functions for the same purpose as the corresponding back stop in the first embodiment of my invention.

A table 115 is secured by arms 116 to the upright bars 86 while a receiver 117 is secured to 105 the uprights 86 by arms 118 for the reception of the copied sheet. The table 115 carries laterally adjustable sheet side guides 119 between which the master sheet is fed to the impression band and thereafter the copy sheets are likewise 110 fed to the impression band.

115 In operating the present embodiment of my invention with the platen roller in the elevated position shown in Figure 16, a master sheet is placed on the table 115 and side guides 119 are adjusted with respect thereto. The sheet is then advanced until its front edge engages the element 113, whereupon the bar 91 is pressed down, thereby pressing down the slides 98 until the latch fingers 120 engage in the apertures 121 of the 120 latch bars 98 and hold the platen roller between the gripping rollers 106, 107. This downward movement causes the rollers 106 and 107 to press against the platen roller 100 because of the link connections 110, and thereby enables the paper 125 to be fed through the platen unit in the manner to lay the master sheet in full surface contact on the impression band, after which it is stripped by hand from the impression band. The bar 91 serves as a handle by which the platen unit may 130 be swung on its pivotal axis 87 from a starting position to a finishing position, during which time the sheet is rolled over the traversed surface of the gelatinous band and leaves its impression thereon. As soon as the platen unit has been 135 moved to the position where the adjustable stops 97 are engaged by the release fingers 96, the latches 94 will be released from the slides 98 which will permit the springs 103 to function to raise the platen roller and spread the gripping 140 rollers apart, thereby positioning them ready for the reception of the next sheet (copy sheet). The platen unit is then swung back to the initial position and a copy sheet is placed between the side guides 119 and into contact with the stop 145 113, whereupon the cycle of operations is repeated for the copy sheet and the copy sheet is discharged onto the paper receiver 117.

150 The link arrangement 110 illustrated in the second embodiment of my invention is also adapt-

ed for use in the first embodiment if so desired as will be obvious to those skilled in the art.

Pivoted on a shaft 123 journalled in the heads of the drum is a moistening device consisting of 5 radial arms 124 carrying a trough-like member 125 in which is secured a strip of felt 126 or other suitable material. The length of the arms 124 is such that by turning the shaft 123 and swinging the arms laterally the felt 126 may be 10 brought into contact with the gelatinous band at a point adjacent the fixedly rotated rollers 82, and thus when the felt 126 is moistened it may be used to apply moisture to the gelatinous surface regardless of the amount of the band wound 15 upon the take-up spools. When not in use the moistening device is positioned as indicated in Figures 3 and 4.

Attention is called to the fact that where the platen roller operates always under the same pressure, the later made copies are of a paler and more indistinct nature than the earlier ones (assuming that the pressure has been adjusted for a clear copy in the beginning). By providing the tension adjusting means for the springs which 25 force the platen roller toward the bed, it is possible, by increasing the tension from time to time as copies are being made, to obtain impressions of an almost uniform degree over a very much larger number of copies than have been heretofore possible.

The provision which I have made for perfect registration (side guides on the table and front edge stop element) make it possible to place the master sheet on the impression pad or surface in 35 a most convenient manner, and it is apparent that precise registration is thereby assured for the following blank or copy sheets which it is intended to print.

It will also have been noticed from the foregoing that my machine is extremely simple in 40 construction and operation. Dependable duplication with least effort and most economy is had since the impression band is protected in the course of operation by the least possible contact 45 (i.e. contact) with the blank sheets to be printed.

It is also to be noted that by virtue of the adjustable cams 71, 72, 73 only such length of the impression band as is actually to be used in printing is permitted to be contacted by the platen 50 roller, thus protecting the impression band from undue wear. In other words, the platen roller is held clear of the impression band throughout 55 all its length except that portion on which the impression to be used is located.

When I have heretofore referred to the impression band as a gelatinous band and when I shall for convenience of description do likewise in the following claims, I wish it understood that the word "gelatinous" is not to be construed as 60 a word of limitation since bands of other suitable material may be used as substitutes, or equivalents, the composition of the bands per se not being of the essence of the present invention.

From the foregoing description, taken in connection with the accompanying drawings, it is 65 thought the construction, operation and advantages of my invention will be clear to those skilled in the art to which it relates.

What I claim is:

1. In duplicating apparatus, the combination 70 with a bed, a gelatinous band sustained thereon, of a platen unit comprising a support, a platen roller, means mounting said roller on said support for movement toward and from the bed, paper gripping rollers located at the front and back of

the platen roller, means mounting said paper gripping rollers on said support for cooperation with said platen roller whereby the paper will pass over the gripping rollers and under the platen roller, means to move said platen roller mounting means to remove and restore said platen roller from and to cooperation with said bed, and means in virtue of which relative movement may be imparted between said bed and said platen unit to cause said platen roller to traverse said gelatinous band for the purpose described. 80

2. In duplicating apparatus, the combination with a bed, a gelatinous band sustained thereon, of a platen unit comprising a support, a platen roller, means mounting said roller on said support for movement toward and from the bed, paper gripping rollers located at the front and back of the platen roller, means mounting said paper gripping rollers on said support for cooperation with said platen roller whereby the paper will pass over the gripping rollers and under the platen roller, means to move said platen roller mounting means to remove and restore said platen roller from and to cooperation with said bed, and means in virtue of which relative movement may be imparted between said bed and said platen unit to cause said platen roller to travel back and forth over said gelatinous surface for the purpose described. 90

3. In duplicating machines, a stationarily mounted cylindrical bed, means to sustain a gelatinous band on said bed, a platen roller, means mounting said roller to move radially of the bed, means tending to press said roller to said bed, means by which relative movement may be set up 100 between said platen unit and bed to cause said platen roller to roll over the periphery of the bed, and means governed by such movement for moving said platen roller away from the bed at times for the purposes described. 110

4. In duplicating machines, a stationarily mounted cylindrical bed, means to sustain a gelatinous band on said bed, a platen roller, means mounting said roller to move radially of the bed, means tending to press said roller to said bed, 120 means by which relative movement may be set up between said platen unit and bed to cause said platen roller to roll over the periphery of the bed, and means governed by such movement for moving said platen roller away from the bed at 125 times for the purposes described, said governed means including a camming element on said bed and an engaging element on said roller mounting means.

5. In duplicating machines, a cylindrical bed, 130 means to sustain a gelatinous band on said bed, a platen roller, means mounting said roller to move radially of the bed, means tending to press said roller to said bed, means by which relative movement may be set up between said platen unit 135 and bed to cause said platen roller to roll over the periphery of the bed, and means governed by such movement for moving said platen roller away from the bed at times for the purposes described, paper gripping rollers cooperatively associated with said platen roller for holding a copy sheet around the same, means mounting said gripping rollers in position whereby said platen roller may be moved between said gripping rollers, or to a position beyond the same, accordingly as 145 said platen roller mounting means is moved in one direction or the other.

6. In duplicating machines, a cylindrical bed, means to sustain a gelatinous band on said bed, a platen roller, means mounting said roller to 150

- move radially of the bed, means tending to press said roller to said bed, means by which relative movement may be set up between said platen unit and bed to cause said platen roller to roll over the 5 periphery of the bed, and means governed by such movement for moving said platen roller away from the bed at times for the purposes described, said governed means including a camming element on said bed and an engaging element on said 10 roller mounting means, paper gripping rollers co-operatively associated with said platen roller for holding a copy sheet around the same, means mounting said gripping rollers in position whereby said platen roller may be moved between said 15 gripping rollers, or to a position beyond the same, accordingly as said platen roller mounting means is moved in one direction or the other.
7. In duplicating machines, a cylindrical bed, means to sustain a gelatinous band on said bed, 20 a platen roller, means mounting said roller to move radially of the bed, means tending to press said roller to said bed, means by which relative movement may be set up between said platen unit and bed to cause said platen roller to roll over the 25 periphery of the bed, and means governed by such movement for moving said platen roller away from the bed at times for the purposes described, a pair of spaced apart gripping rollers, and means for pressing said gripping rollers 30 yieldably against said platen roller when said platen roller is located between said gripping rollers.
8. In duplicating machines, a cylindrical bed, means to sustain a gelatinous band on said bed, 35 a platen roller, means mounting said roller to move radially of the bed, means tending to press said roller to said bed, means by which relative movement may be set up between said platen unit and bed to cause said platen roller to roll over the 40 periphery of the bed, and means governed by such movement for moving said platen roller away from the bed at times for the purposes described, said governed means including a camming element on said bed, and an engaging element on said roller mounting means, a pair of 45 spaced apart gripping rollers, and means for pressing said gripping rollers yieldably against said platen roller when said platen roller is located between said gripping rollers.
- 50 9. In duplicating machines, a cylindrical bed, means to sustain a gelatinous band on said bed, a platen roller, means mounting said roller to move radially of the bed, means tending to press said roller to said bed, means by which relative 55 movement may be set up between said platen unit and bed to cause said platen roller to roll over the periphery of the bed, and means governed by such movement for moving said platen roller away from the bed at times for the purposes described, a pair of spaced apart gripping rollers, and means for 60 pressing said gripping rollers yieldably against said platen roller when said platen roller is located between said gripping rollers, said pressing means including pivoted roller carrying arms and springs 65 associated therewith to tend to close the arms together.
10. In duplicating machines, a cylindrical bed, means to sustain a gelatinous band on said bed, a platen roller, means mounting said roller to move radially of the bed, means tending to press said roller to said bed, means by which relative movement may be set up between said platen unit and bed to cause said platen roller to roll over the periphery of the bed, and means governed by such movement for moving said platen 75 roller away from the bed at times for the purposes described, said governed means including a camming element on said bed and an engaging element on said roller mounting means, a pair of spaced apart gripping rollers, and means for 80 pressing said gripping rollers yieldably against said platen roller when said platen roller is located between said gripping rollers, said pressing means including pivoted roller carrying arms and springs associated therewith to tend to close the arms together.
11. In duplicating machines, a cylindrical bed, means to sustain a gelatinous band on said bed, a platen roller, means mounting said roller to move radially of the bed, means tending to press said roller to said bed, means by which relative movement may be set up between said platen unit and bed to cause said platen roller to roll over the periphery of the bed, and means governed by such movement for moving said platen roller away from the bed at times for the purposes described, a pair of spaced apart gripping rollers, and means for 90 pressing said gripping rollers yieldably against said platen roller when said platen roller is located between said gripping rollers, and a paper stop element mounted on the arm which carries the out-feed one of said pressing rollers.
12. In duplicating machines, a cylindrical bed, means to sustain a gelatinous band on said bed, a platen roller, means mounting said roller to move radially of the bed, means tending to press said roller to said bed, means by which relative movement may be set up between said platen unit and bed to cause said platen roller to roll over the periphery of the bed, and means governed by such movement for moving said platen roller away from the bed at times for the purposes described, said governed means including a camming element on said bed and an engaging element on said roller mounting means, a pair of spaced apart gripping rollers and means for 100 pressing said gripping rollers yieldably against said platen roller when said platen roller is located between said gripping rollers, and a paper stop element mounted on the arm which carries the out-feed one of said pressing rollers.
13. In duplicating machines wherein is provided a bed unit and a platen unit, said platen unit comprising a carrying frame which includes side plates having slideways, slides movable in said slideways, a platen roller carried by said slides, said slides in their movement functioning to carry said roller toward and from the bed unit, a pair of paper gripping rollers one at each 110 side of the platen roller, means moving said gripping rollers toward said platen roller to hold the paper in contact therewith when said platen roller is in proximity to said gripping rollers, said platen roller being arranged to be elevated above 115 the out-feed one of said pressing rollers.
14. In duplicating machines wherein is provided a bed unit and a platen unit, said platen unit comprising a carrying frame which includes side plates having slideways, slides movable in said slideways, means continuously tending to move said slides in one direction, said slides in their movement functioning to carry said roller toward and from the bed unit, a pair of paper 125 gripping rollers one at each side of the platen roller, means moving said gripping rollers toward said platen roller to hold the paper in contact therewith when said platen roller is in proximity to said gripping rollers, said platen roller being 130 elevated above the out-feed one of said pressing rollers.
15. In duplicating machines wherein is provided a bed unit and a platen unit, said platen unit comprising a carrying frame which includes side plates having slideways, slides movable in said slideways, means continuously tending to move said slides in one direction, said slides in their movement functioning to carry said roller toward and from the bed unit, a pair of paper 140 gripping rollers one at each side of the platen roller, means moving said gripping rollers toward said platen roller to hold the paper in contact therewith when said platen roller is in proximity to said gripping rollers, said platen roller being 145 elevated above the out-feed one of said pressing rollers.

- arranged to be elevated above said gripping rollers at times for the insertion of paper sheets.
15. In duplicating machines wherein is provided a bed unit and a platen unit; said platen unit comprising a carrying frame which includes side plates having slideways, slides movable in said slideways, a platen roller carried by said slides, said slides in their movement functioning to carry said roller toward and from the bed unit, a pair of paper gripping rollers one at each side of the platen roller, means moving said gripping rollers toward said platen roller to hold the paper in contact therewith when said platen roller is in proximity to said gripping rollers, said platen roller being arranged to be elevated above said gripping rollers at times for the insertion of paper sheets, and a paper stop element cooperatively associated with one of said rollers.
- 20 16. In duplicating machines wherein is provided a bed unit and a platen unit; said platen unit comprising a carrying frame which includes side plates having slideways, slides movable in said slideways, a platen roller carried by said slides, said slides in their movement functioning to carry said roller toward and from the bed unit, a pair of paper gripping rollers one at each side of the platen roller, means moving said gripping rollers toward said platen roller to hold the paper in contact therewith when said platen roller is in proximity to said gripping rollers, said platen roller being arranged to be elevated above said gripping rollers at times for the insertion of paper sheets, and a combined paper stop and paper deflector element associated with said rollers and serving, when in one position, to act as a stop gauge for the fore edge of the inserted paper sheet to be printed, and serving, when in another position, as a means to deflect the sheet from the gripping roller on the out-feed side for discharging purposes.
- 25 17. In duplicating machines wherein is provided a bed unit and a platen unit; said platen unit comprising a platen roller, paper gripping rollers cooperating with said platen roller, means for mounting said platen roller for movement in a general plane toward and from the bed, means for mounting said gripping rollers for movement from and toward one another transversely of said general plane, and means for moving said platen roller in its general plane into and out of cooperative position with respect to said gripping rollers.
- 30 18. In duplicating machines wherein is provided a bed unit and a platen unit; said platen unit comprising a platen roller, paper gripping rollers cooperating with said platen roller, means for mounting said platen roller for movement in a general plane toward and from the bed, means for mounting said gripping rollers for movement from and toward one another transversely of said general plane, means for moving said platen roller in its general plane into and out of cooperative position with respect to said gripping rollers, and a combined paper stop and deflector element mounted adjacent said platen roller to overlie the out-feed one of the gripping rollers and be engaged by said platen roller for the purposes described.
- 35 19. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said pawl shifting and holding elements having spring-pressed plungers for yieldably holding the pawls in engagement with their respective ratchets.
- 40 20. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said ratchets having shafts journaled in bearings in said bed and having slotted sockets, said spools having shaft ends to fit into said sockets, and spring clips on said shafts to close the slots and retain said shaft ends in place.
- 45 21. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said ratchets having shafts journaled in bearings in said bed and having slotted sockets, said spools having shaft ends to fit into said sockets, and spring clips on said shafts to close the slots and retain said shaft ends in place, and means retaining said ratchets in place on the bed during placement and removal of the spools.
- 50 22. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said bed being of cylindrical form and said band overlying the periphery thereof, said spools being located within the cylinder, the periphery of said cylinder being open in part to permit said band to pass to and from said spools, and spreaders carried by said band within the cylinder, means to mount said spreaders whereby they may be projected outwardly to lift the band clear of the periphery of the cylinder for the purposes described.
- 55 23. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said bed being of cylindrical form and said band overlying the periphery thereof, said spools being located within the cylinder, the periphery of said cylinder being open in part to permit said band to pass to and from said spools, and spreaders carried by said band within the cylinder, means continuously tending to project said spreaders outwardly upon slackening up on the tension of the band.
- 60 24. In duplicating machines wherein is pro-
- 65 70 75 80 85 90 95 100 105 110 115 120 125 130 135 140 145 150

- vided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said bed being of cylindrical form and said band overlying the periphery thereof, said spools being located within the cylinder, the periphery of said cylinder being open in part to permit said band to pass to and from said spools, and spreaders carried by said band within the cylinder, means swingably mounting said spreaders in said bed, said spreaders being adapted to be swung out beyond the periphery of said bed.
25. In duplicating machines wherein is provided a fixed unit and a movable unit associated therewith; one of said units comprising a bed, a printing band overlying said bed, spools for said band, means by which said spools may be turned to shift said band, ratchets cooperating with said spools, double-acting pawls cooperating with said ratchets, and pawl shifting and holding elements cooperating with said pawls, said bed being of cylindrical form and said band overlying the periphery thereof, said spools being located within the cylinder, the periphery of said cylinder being open in part to permit said band to pass to and from said spools, and spreaders carried by said band within the cylinder, means swingably mounting said spreaders in said bed, said spreaders being adapted to be swung out beyond the periphery of said bed, and means continuously tending to swing said spreaders outwardly for the purposes specified.
26. In duplicating machines, a stationarily located bed, means to sustain an impression surface on said bed, a platen roller, means mounting said roller to move toward and from the plane of the bed, means tending to press said roller to said impression surface, means by which relative movement may be set up between said platen unit and said bed to cause said platen roller to roll over the surface of the impression surface on the bed, and means whereby said platen roller pressing means may be rendered operative only over that much of the area of the impression surface as contains the impression to be printed.
27. In duplicating machines, a stationarily located bed, means to sustain an impression surface on said bed, a platen roller, means mounting said roller to move toward and from the plane of the bed, means tending to press said roller to said impression surface, means by which relative movement may be set up between said platen unit and said bed to cause said platen roller to roll over the surface of the impression surface on the bed, and means whereby said platen roller pressing means may be rendered operative only over that much of the area of the impression surface as contains the impression to be printed, and means for effecting positive registration in placing the master sheet and succeeding copy sheets on the impression surface.
28. In duplicating machines, a bed, means to sustain a gelatinous band on said bed, a platen roller, means mounting said roller to move toward and from the bed, means tending to press said roller to said bed, means by which relative movement may be set up between said platen unit and bed to cause said platen roller to roll over the surface of the bed, and means governed by such movement for moving said platen roller away from the bed at times for the purposes described, and means for adjusting the degree of pressure applied by said means tending to press.
29. In duplicating machines wherein is provided a bed on which an impression band is located and spools on which said band is adapted to be wound; the combination with the aforesaid structure, of means for applying moisture to the gelatinous surface adjacent to either spool.
30. In duplicating machines wherein is provided a drum on the periphery of which is held a gelatinous band and spools located within the drum on which the ends of the band are wound; the combination with the aforesaid structure, of a moistening device located within the drum between the spools and adapted to apply moisture to the gelatinous band adjacent either spool as desired.
31. In duplicating machines wherein is provided a bed on which an impression band is located and spools on which said band is adapted to be wound; the combination with the aforesaid structure, of means for applying moisture to the gelatinous surface adjacent to either spool, said moistening means comprising a holder, an applicator strip adapted to absorb moisture carried by said holder, and pivoted arms for supporting the holder, said arms being adapted to be swung on their pivots to bring said applicator strip into contact with the gelatinous band adjacent either spool accordingly as said arm is swung in one direction or the other.
32. In duplicating machines wherein is provided a drum on the periphery of which is held a gelatinous band and spools located within the drum on which the ends of the band are wound; the combination with the aforesaid structure, of a moistening device located within the drum between the spools and adapted to apply moisture to the gelatinous band adjacent either spool as desired, said moistening means comprising a holder, an applicator strip adapted to absorb moisture carried by said holder, and pivoted arms for supporting the holder, said arms being adapted to be swung on their pivots to bring said applicator strip into contact with the gelatinous band when desired.
33. In duplicating apparatus, a bed unit, a platen roller, and means co-operating with the platen roller for feeding and removing copy sheets to and from said bed unit with a progressive line contact, said co-operating means comprising rollers disposed on opposite sides of said platen roller and co-operating therewith to advance the sheets between them and the platen roller.
34. In duplicating apparatus, a bed unit, a platen roller, and means co-operating with the platen roller for feeding and removing copy sheets to and from said bed unit with a progressive line contact, said co-operating means comprising rollers disposed on opposite sides of said platen roller and co-operating therewith to advance the sheets between them and the platen roller, and means for raising and lowering said platen roller from and toward, respectively, from said bed unit.
35. In duplicating apparatus, a bed unit, a platen roller, and means co-operating with the platen roller for feeding and removing copy sheets to and from said bed unit with a progressive line contact, said co-operating means comprising rollers disposed on opposite sides of said platen roller and co-operating therewith to advance the sheets between them and the platen

roller, and means including resilient means for displacing said platen roller bodily toward and away from said bed unit.

36. In duplicating apparatus, a bed unit, a platen roller, and means co-operating with the platen roller for feeding and removing copy sheets to and from said bed unit with a progressive line contact, said co-operating means comprising rollers disposed on opposite sides of said platen roller and co-operating therewith to advance the sheets between them and the platen roller, and means including a cam for displacing said platen roller bodily toward and away from said bed unit.

15

20

37. In duplicating apparatus, a bed unit, a platen roller, means for causing relative movement between said bed unit and said platen roller, an adjustable cam for displacing said platen roller bodily toward and away from said bed unit, said cam being adjustable to determine the time in each operation said platen roller is raised out of operative relationship with said bed unit, and rollers adjacent the platen roll for guiding paper to be duplicated part of the way around the platen roll.
